UNITED STATES PATENT OFFICE.

EDGAR FRANKLIN HILL, OF SPRINGFIELD, MASSACHUSETTS.

JOINTED FIGURE TOY.

Application filed March 2, 1927. Serial No. 172,100.

The present invention relates to articulated stuffed cloth toys, such as animal and other figure toys, dolls, and the like, and aims generally to improve such toys.

- 5 An especial object of the invention is to improve the joints of such toys, particularly that between the head and body, by providing a strong, simple, and efficient means for connecting two articulated portions whereby 10 one portion may be easily and quickly adjusted to any one of a large number of angular positions with respect to the other portion, and thereby increase the attractiveness and salability of the toy.
- 15 Other objects and advantages of the invention will be apparent from the following description of the toy dog depicted in the accompanying drawings, wherein:

Fig. 1 is a front view of the toy showing 20 the head in two positions,

Fig. 2 is an enlarged fragmental sectional view illustrating the manner of connecting the head and body portions together, and

Fig. 3 is a disassembled view of the 25 several parts constituting the improved connection.

Referring to the illustrative embodiment of the invention shown in the drawings, the toy comprises the body portion having a 30 fabric casing 10 and a fibrous stuffing 11, and a head portion having a fabric casing 12 and a fibrous stuffing 13. The casings 10 and 12 are suitably shaped and decorated to resemble a desired object, herein illustrated 35 as a dog.

According to my invention the improved connecting means, herein illustrated as between the body and head portions, permits relative movement and adjustment of one 40 portion both rotatively about the axis of the connection and angularly in all directions crosswise or diametrically of the axis of the connection, and also permits relative movement in an orbital path around the axis of 45 the connection, or any combination of two or more of these adjustments. In the illustrated form of the invention, the connection comprises multiple dished-shaped discs in frictional engagement with each other, and 50 held together centrally so as to constitute a floating universal connection or joint. As shown in the drawings, the disc member 14 is suitably secured within and to the casing 12 so that its convex face is adjacent the 55 body, and the disc member 15 is suitably secured with and to the neck portion of the

body casing 10 so that its concave face is presented to the convex face of the disc 14 on the head. The disc member 15 is provided with an enlarged central opening 16, 60 herein shown as a circular opening, and is pierced by a suitable fastening means, as for instance a stud 17, carried by the disc 14 and of materially less diameter than the opening 16. An anchor disc 18 is loosely 65 mounted on the stud 17 and frictionally engages the inner convex face of the body disc 15. In order to reduce the friction between the head and body portions to a degree sufficient to hold the head in any of its adjusted 70 positions, and to permit of easier movement of the head to adjust it, I provide a spacer disc 19, of reduced diameter with respect to the discs 14 and 15, secured to the stud 17 and interposed between the discs 14 and 15. 75 Thus the frictional contact between the discs 14 and 15 is proportionate to the area of the disc 19, the size of which may be varied independently upon the purpose desired.

Means are advantageously provided for 80 holding the discs in yielding frictional engagement with each other, and according to the illustrated form of the invention, a spring 20 surrounds the stud 17 between the rear face of the anchor disc 18 and a 85 removable stop member 21, as for instance a washer, secured to the stud by suitable means, as for instance a screw 22 threaded into the stud 17. This construction permits of yielding frictional engagement of the 90 several discs to hold the head in its adjusted position, and also permits of movements of the discs toward or from each other in the direction of the axis of the stud, to accommodate fabrics of various thicknesses. 95

Advantages of the invention lie in the simplicity and cheapness of construction and the ease with which the connection can be incorporated in the construction of such toys. Furthermore, toys constructed according to my invention are unique in that they may be adjusted to many attractive 100 positions not heretofore possible on similar toys.

My invention is not to be restricted to the 105 details of construction shown and described.

What I claim is:

1. An improved toy figure comprising a stuffed cloth body and a stuffed cloth head, said body and head having interfitting convex and concave portions, and means for movably connecting said body and head 110

including relatively movable cooperating convex and concave members attached to the convex and concave portions respectively, one of said members carrying a stud and the other an enlarged opening through which said stud extends, whereby said head may be turned axially with respect to the body or adjusted angularly with respect thereto, or both, resilient means on the stud for urging said members together, a second convex member carried by said stud and frictionally engaging the rear face of said concave member and cooperating with said resilient means to hold said head in any of its adjusted positions.

2. An improved toy figure comprising a stuffed cloth body and a stuffed cloth head, said body 10 and head 12 having interfitting convex and concave portions and means for connecting said body and head including a convex member 14 of relatively stiff material within the head member and conforming to the convex portion thereof, a concave member 15 of relatively stiff material within the concave portion of the body, a stud member 17 carried by the convex member of the head and extending rearwardly through the concave member within the body, a member 18 of sheet material carried by said stud rearwardly of said concave member and shaped to frictionally cooperate with the adjacent face of said concave member, said concave member 15 being formed with an enlarged opening 16 surrounding said stud whereby said head may be turned axially with respect to said body or adjusted angularly with respect thereto, or both, and resilient means 20 on the stud for urging said members together whereby to hold said head in any of its adjusted positions.

3. An improved toy figure comprising a stuffed cloth body and a stuffed cloth head, said body 10 and head 12 having interfitting convex and concave portions and means for connecting said body and head including a convex member 14 of relatively stiff material within the head member and conforming to the convex portion thereof, a concave member 15 of relatively stiff material within the concave portion of the body, a stud member 17 carried by the convex member of the head and extending rearwardly through the concave member within the body, a member 18 of sheet material carried by said concave member and being shaped to frictionally cooperate with the adjacent face of said concave member, said concave member 15 being formed with an enlarged opening 16

surrounding said stud whereby said head 60 may be turned axially with respect to said body or adjusted angularly with respect thereto, or both, an abutment 21 on the end of the stud, and spring means between the abutment 21 and the member 18 for urging 65 said members together to hold said head in any of its adjusted positions.

4. An improved toy figure comprising a stuffed cloth body and a stuffed cloth head and means movably connecting said body 70 and head permitting of adjustment of one relative to the other to any one of many positions, said means including a convex member secured to the head and having a longitudinal stud extending rearwardly 75 therefrom, a concave member secured to said body and loosely surrounding said stud, a spacing member surrounding said stud and interposed between said convex and concave means and resilient means surrounding said stud for urging said convex and concave members into frictional engagement with each other.

5. In an improved stuffed cloth toy figure, a means for securing relatively movable 85 parts thereof together for universal adjustment comprising a convex member secured to one part and having a fastening member projecting therefrom, a concave member secured to the other cooperating part and 90 loosely surrounding said fastening member, a spacing member surrounding said fastening member and interposed between said convex and concave members, and means associated with said fastening means for 95 resiliently holding said members in yielding assembled relation.

6. An improved toy figure comprising a stuffed cloth body and a stuffed cloth head and means movably connecting said body 100 and head permitting of adjustment of one relative to the other to any one of many positions, said means including a convex member secured to the head and having a longitudinal stud extending rearwardly 105 therefrom, a concave member secured to said body and loosely surrounding said stud; a spacing member surrounding said stud and interposed between said convex and concave means, said spacing member 110 being of smaller size than either the convex or concave members thereby to decrease the area of frictional contact between them, and means for holding said members in assembled relation.

In testimony whereof, I have signed my name to this specification.

EDGAR FRANKLIN HILL.
